UNITED STATES PATENT OFFICE.

GEORGE A. MELLON, OF ST. LOUIS, MISSOURI, ASSIGNOR TO LINK FABRIC COMPANY OF AMERICA, OF ST. LOUIS, MISSOURI, A CORPORATION.

BED-BOTTOM FABRIC.

1,081,620.

Specification of Letters Patent.

Patented Dec. 16, 1913.

Application filed May 31, 1913. Serial No. 771,006.

To all whom it may concern:

Be it known that I, GEORGE A. MELLON, a citizen of the United States of America, and a resident of the city of St. Louis and 5 State of Missouri, have invented certain new and useful Improvements in Bed-Bottom Fabrics, of which the following is a full, clear, and exact description, reference being had to the accompanying drawings, 10 forming a part of this specification.

My invention relates to that character of bed bottom fabrics in which there are longitudinal wires and transverse connections joining the series of longitudinal wires at 15 intervals.

The present invention has for one of its objects the production of a fabric of this kind including elastic and flexible transverse connections between the longitudinal wires, 20 which permit yielding of the longitudinal wires relative to each other transversely of the fabric, while they maintain the longitudinal wires in their proper relative positions with a degree of effectiveness similar to that 25 provided by non-yielding transverse connections.

A further object of my invention is to produce a fabric of this kind which may be readily rolled into compact condition for 30 transportation.

A still further object of the invention is to provide transverse connections for a bed bottom fabric which may be applied to the longitudinal wires of such fabric with a 35 minimum of labor for their application.

Figure I is a top or plan view of a fragment of my bed bottom fabric. Fig. II is a section taken on line II-II, Fig. I.

The preferred form of my bed bottom 40 fabric is shown in the accompanying drawing. In this fabric, A designates longitudinal wires or strands comprising series of links joined to each other in chain formation. Each of these links is made from a 45 section of wire doubled to provide an eye 2 at one end of the link, the links terminating at their other ends in double hooks 3. The eyes of the links in each transverse row

receive the hooks of the links in the next adjoining transverse row, this procedure being followed throughout the length of the fabric and resulting in the production of the longitudinal strands A. The production of longitudinal strands in this manner is not new, and no invention *per se* is herein 55 claimed therefor.

4 designates transverse connections by which the longitudinal strands A of my bed bottom fabric are united to maintain them in their proper positions. These connections 60 4 are of helical form, and they are placed in engagement with the longitudinal strands A by interweaving or threading them through said strands. In the link strand construction illustrated, the helical connections 65 4 are threaded through the loops of the transverse rows of links, and also through the hooks of the links in the adjoining transverse rows, by which arrangement the links throughout the fabric structure are held from movement relative to each other in the strands, and the various longitudinal strands are so united as to permit lateral movement of any strand relative 70 to another adjacent strand, and the return 75 of the strand to its original position, these results being due to the spring and flexing nature of the helical connections.

I claim:

1. A bed bottom fabric comprising longitudinal strands, and helical connections having interwoven engagement with said longitudinal strands. 80

2. A bed bottom fabric comprising longitudinal strands, and helical transverse connections having interwoven engagement 85 with said longitudinal strands, the said connections extending throughout the width of the fabric.

3. A bed bottom fabric comprising longitudinal strands, each strand being composed of a plurality of links joined to each other, and helical transverse connections joining 90 said links.

4. A bed bottom fabric comprising longitudinal strands, each strand being composed 95

of a plurality of links joined to each other, and helical connections interwoven with said links at their junctions.

5. A bed bottom fabric comprising longitudinal strands, each strand being composed of links having eyes at one end and hooks at the other end, the eyes and hooks being

interengaged with each other, and helical connections woven through the eyes of said links to join said longitudinal strands.

GEORGE A. MELLON.

In the presence of--
E. CLARK,
E. LINN.
